Walter Appold, Jr.

UNITED STATES PATENT OFFICE.

HENRY J. STUART, OF ANSONIA, CONNECTICUT, ASSIGNOR TO THE ROBERT N. BASSETT COMPANY, OF SHELTON, CONNECTICUT, A CORPORATION OF CONNECTICUT.

GARMENT-SUPPORTER.

1,145,939.

Specification of Letters Patent. Patented July 13, 1915.

Application filed June 11, 1912. Serial No. 703,014.

To all whom it may concern:

Be it known that I, HENRY J. STUART, a citizen of the United States, residing at Ansonia, in the county of New Haven and State of Connecticut, have invented a certain new and useful Improvement in Garment-Supporters, of which the following is a specification.

My invention relates to hose supporters and its object is to provide a device of this character in which the expedient of sewing the supporting strap and button tab can be entirely eliminated. I attain this and other objects of my invention in the preferred embodiment thereof set forth in the following description and accompanying drawing in which like reference characters refer to corresponding parts.

In the drawing: Figure 1 is a front view of my hose supporter; Fig. 2, an enlarged fragmentary longitudinal section; Fig. 3, an enlarged fragmentary rear view, and Fig. 4, an enlarged fragmentary view showing the parts in position to be assembled.

My invention generally comprises the supporting strap A, the binder B, the button loop C and the button tab D which latter carries a button E. The binder B is suitably blanked out of sheet metal and folded on itself to form a pair of gripping lips 2 and 3 each of which is pierced inwardly to form spurs 4, 4. The bend 5 in the binder is provided with a slot 6 which is equal in length to the width of the tab D. The lower end 7 of the supporting strap A, the upper end 8 of the button tab D and the inwardly projecting pintles 9, 9, forming the top side of the loop C, are all fastened within the binder in a manner which will hereinafter be described. In forming the binder the lips 2 and 3 are left open or at an angle to each other as shown in Fig. 4.

In assembling the parts the end 8 of the tab D is threaded through the slot 6 from the outside after which it is grasped by the fingers of the operator and drawn through the binder until its end 8 projects beyond the edges of the lips. The loop C is then passed over the lip 2 and the pintles 9, 9 drawn down against the end 8 of the tab at or immediately adjacent to the bend 5 in the binder. The upper opening in the loop is slightly narrower than the length of the lip 2, so that, when the loop is passed over the lip, its sides strike against the beveled corners b, b thereby causing the pintles to spread or spring apart as the loop is drawn down toward the bend 5. This springing action of the loop causes the same to frictionally engage the sides of the fold and enables the pintles to become seated and to hold the end of the tab in place during that part of the assembling operation in which the lips remain open. After the loop is sprung into the binder the button E is passed into its widened portion and drawn down so that its shank engages the bottom of the narrow portion in the usual manner of fastening the button in the loop. This drawing down of the button also draws down on the tab which latter slips back again through the slot until the tab is taut between the button and the binder. This method of assembling the tab not only may be accomplished with great speed but also prevents the same from being left too long or too short to properly coöperate with the loop. The slot 6 being of the same width as the tab centers the same in the binder when the tab is pulled back by the button. The tab, loop and binder thus assembled may without the supporting strap form an article of manufacture suitable for the trade, since it is sometimes the custom for corset and hose supporter firms to purchase the parts thus assembled and fasten thereto their own straps or webbing. To fasten the supporting strap it is merely necessary to insert the end 7 between the lips 2 and 3, or to be more exact, between the lip 2 and the end 8 of the tab, and then to swage the lips together on to the ends of the strap and tab. The gripping action of the lips, if desired, may be supplemented by the penetrating spurs 4, 4. When the thickness of the wire forming the pintles 9, 9 is greater than the combined thickness of the ends of the tab and strap the swaging of the lips on to the ends of these latter causes the bend 5 of the binder to draw tightly around the pintles and thereby forms a cylindrical sleeve which incases the pintles and that part of the tab end passing around one side of the pintles. A crimp a is thus formed in the tab end, which taken together with the gripping action of the lips and binding action of the tab around the rear edge of the slot 6, securely fastens the tab end within the binder so that it cannot be pulled out when grasped by the wearer to pull down or stretch the

supporter. It should be noticed that a minimum length of tape and webbing may be used in forming the tab and strap since no waste occurs at the binder in doubling or folding the extremities. For this same reason the supporter is very flat and thin and presents a substantially flush surface on both its front and rear faces. It should be further noticed that the side edges of the 10 supporting strap are unconfined so that the same size binder may be used on different widths of webbing.

Although the device above described embodies the preferred form of my invention yet the same is susceptible to such modifications as may fairly come within the scope 15 of the appended claims.

Having now described my invention what I claim and desire to protect by Letters Patent is:

1. As an article of manufacture the combination with a button loop and button tab, of a binder made out of a single piece of sheet metal bent up to present a pair of

open web-gripping lips, the bend in the 25 binder being slotted transversely to admit the free end of the tab into the binder, and the button loop having its top side sprung into the bend beside the end of the tab so as to frictionally engage the sides of the bend 30 to hold the tab in engagement with the binder.

2. As an article of manufacture a garment supporter comprising a supporting strap, a button loop, and button tab and a sheet 35 metal binder having a pair of gripping lips joined by a bend, the lips being swaged on to the ends of the strap and tab, the bend being transversely slotted to admit the end of the tab into the binder, and the top side of the 40 loop being seated beside the tab inside the bend to form a crimp in the tab end.

Signed at Ansonia, Connecticut this 29th day of May, 1912.

HENRY J. STUART.
